UNITED STATES PATENT OFFICE.

CHARLES C. BLAKE, OF BROOKLINE, AND MARK E. FERNALD, OF SAUGUS, MASSACHUSETTS.

WORK-SUPPORT.

1,373,114.

Specification of Letters Patent. Patented Mar. 29, 1921.

Original application filed April 14, 1915, Serial No. 21,424. Divided and this application filed March 17, 1916. Serial No. 84,802.

To all whom it may concern:

Be it known that we, CHARLES C. BLAKE and MARK E. FERNALD, citizens of the United States, residing, respectively, at 5 Brookline, in the county of Norfolk and State of Massachusetts, and at Saugus, in the county of Essex and State of Massachusetts, have invented a new and useful Improvement in Work-Supports, of which the 10 following is a specification.

The present invention relates to shoe machines, and more particularly to work supports therefor.

The objects of the present invention are 15 to simplify and improve the construction and mode of operation of work supports for general use in shoe machines and to provide an efficient work support for the machine disclosed in the application for 20 Letters Patent of the United States filed April 14, 1915, Serial No. 21,424, of which this application is a division.

To the accomplishment of these objects, and such others as may hereinafter appear, 25 the features of the invention consist in certain devices, arrangements, and combinations of parts fully set forth hereinafter, the advantages of which will be readily understood by those skilled in the art.

30 The various features of the invention will be readily understood from an inspection of the accompanying drawings illustrating the best form of the invention at present devised, in which,

35 Figure 1 is a detail in side elevation of a machine embodying the present invention; Fig. 2 is a vertical sectional elevation;

Fig. 3 is a plan; and

40 Fig. 4 is a sectional plan on the line 4—4, Fig. 2, the grippers being removed to show the slots which contain the gripper supports.

45 The embodiment of the invention illustrated in the drawings is provided with a series of grippers 1 (Figs. 1 and 3) herein shown as twenty-five in number, which are arranged around the forepart of a last 2 having assembled thereon the insole and upper and parts within it, hereinafter for 50 brevity termed the "shoe". In drafting a pattern for producing an upper to fit a par-

ticular last the drafter places two lines on the upper surface of the forepart of the last, one of which is called the lead line and the other of which is called the tip-seam 55 line. The lead line lies in a vertical plane bisecting the arch of the last. The tip-seam line lies in a vertical plane perpendicular to the plane of the lead line and is located substantially one-fifth of the length 60 of the last from the tip of the toe. With the lead line as a guide it is a comparatively easy matter to draft a pattern for producing an upper which, when assembled on the last, will have the lacing slit thereon arranged in a vertical plane passed longitudinally through the lead line. It is more difficult when using the tip-seam line on the last as a guide to predetermine the position 65 of the tip-seam on the upper for the reason 70 that the drafter must calculate the amount of longitudinal stretch of the upper so that the tip-seam of the upper will coincide with the tip-seam on the last only after the upper has been stretched on the last. Consequently 75 the tip-seam line on the assembled upper must be located back of the tip-seam line on the last a distance equal to the amount of longitudinal stretch of the upper. After the upper is prepared in the 80 manner described a notch is cut in the tip of the toe which is alined with the lacing slit and the lead line. If the upper is assembled on the last so that the lacing slit and notch lie in a vertical plane passed 85 longitudinally through the lead line it will be apparent that the upper is positioned for the lasting operation in the manner predetermined by the pattern drafter. If the upper is lasted after being assembled in this 90 position the tip-seam line of the upper will be stretched forward to coincide with the tip-seam line on the last. Similarly all the other parts of the upper will be drawn to the wood of the last in a natural position. 95 An attempt to place the upper in any position other than the proper assembled one will only result in straining the upper into an unnatural position on the last resulting in a botch the strained lines of which will 100 soon make their appearance in the use of the shoe.

In our machine we propose to take advantage of the knowledge and skill of the pattern drafter. To this end we center the last in the machine so that the lead line on the last registers with the center line of the machine and we also engage the portion of upper surrounding the notch with a gripper 3 (Fig. 2) which is constrained to move into upper-engaging position in a vertical plane intersecting the notch, the lead line and the lacing slit. Two floating grippers, namely, the grippers 4 and 5, are then engaged with the ends of the tip-seam which are at this time located back of the tip-seam line on the last. After these three grippers, herein called the critical grippers, engage the upper the remaining grippers are caused to engage the upper in an orderly manner. Then when the last and grippers are relatively actuated to impart an updraw movement to the upper the upper is stretched forwardly and transversely. During the updraw movement the gripper 3 continues to operate in the vertical plane intersecting the notch, the lead line and the lacing slit. The grippers 4 and 5, however, turn toward the toe of the shoe under the influence of the toe grippers in stretching the upper longitudinally and thus the tip-seam of the upper is carried forwardly so that it coincides with the tip-seam line on the last. With this construction and mode of operation the upper may be drawn to the wood of the last in the position predetermined for it by the pattern drafter without that adjustment of the upper on the last which is a characteristic feature of the present commercial hand and machine methods of pulling-over.

As shown in Fig. 4 the grippers 4 and 5 and all of the other grippers for lasting the sides of the shoe operate in parallel slots 6 (Fig. 4). The slots 6 which contain the grippers 4 and 5 are arranged in the vertical plane which passes through the tip-seam line of the last. The grippers 3 and all of the other grippers for lasting the toe of the shoe operate in slots 7 which radiate from a common point lying in the vertical plane of the tip-seam line of the last.

The grippers (Fig. 2) comprise a lower jaw 8 and an upper jaw 9. The lower jaw is formed on a bar 10 which is pivoted at 11 to move between plates 12 rising from a carrier 13. The upper jaw is formed on a bar 14 which is pivoted at 15 to the bar 10. The jaws are closed to grip the upper through the manipulation of a handle 16 which is pivoted to a tail 17 on the bar 10 and is connected to the upper jaw 9 by a bar 18. The bar 18 is provided with bends 19 to permit the jaw 9 to yield and thus accommodate itself to varying thicknesses of the upper inserted between the jaws.

The carrier 13 is pinned to a rod 20 rota-

tabley mounted in bearings 21 formed on a support 22 one of which is contained in each of the slots 6 and 7. The support 22 normally rests upon a buffer-spring 23 carried in a spring-cage 24 on the top of the machine frame. The support is provided with a foot 25 having a groove 26 formed thereon which hooks under a rail 27 carried by a base 28 bolted to the top of the machine frame. The rail 27 is curved around the toe and is straight along the sides and incloses an area substantially equal to the projected area of the insole on the last.

In order to constrain the critical gripper 3 to move longitudinally into its gripping position in a vertical plane intersecting the notch, the lead line and the lacing slit, the support 22 therefor carries a yoke 33 (Fig. 2) arranged to hold the bar 10 from turning about the axis of the rod 20 during the upper-engaging movement of the gripper.

In the illustrated embodiment of the invention the last 2 (Fig. 2) having assembled thereon the insole and upper and parts within it, is placed in the machine with the face of the heel of the last engaged with a back rest 34 and with the insole on the last engaged with a heel seat rest 35 and a forepart rest 36. The back rest 34 is provided with a slot 37 for the reception of an assembling tack the head of which usually projects from the face of the heel of the last. The back rest 34 is secured to a slide 39 which is mounted to slide on a guide 40. The guide 40 is interposed between, and secured to, a pair of plates 41 (Fig. 1) integral with a carrier 42 (Fig. 2) which normally rests upon the base 28. The heel seat rest 35 is formed integral with the back rest 34 and is mounted to slide upon the top of the guide 40. The forepart rest 36 is provided with an indicating mark 43 (Fig. 3) arranged in the center line of the machine. The forepart rest 36 is formed on a slide 44 which is mounted to slide between the plates 41 on the top of the carrier 42. To properly position the last laterally as it is moved by the operative against the back rest 34 the slide 39 carries a pair of arms 45 arranged to embrace the face of the heel of the last.

One of the arms is carried by a vertical post 46 which is pivotally mounted in the slide 39. The other arm is loosely mounted on the post 46. With this construction the arms may shift laterally to properly center right and left lasts and may separate more or less to accommodate lasts of different sizes. The arms 45 separate under the pressure of the work introduced between them against the tension of a pair of leaf springs 47 (Figs. 1, and 4) carried by the slide 39.

In order that the lasting devices of the machine may operate upon all sizes and styles of lasts whether rights or lefts without substitution, change or adjustment

thereof the forepart and heel part rests are mounted for adjustment toward and from each other in a differential manner so that the tip-seam line on the last hereinbefore referred to may be uniformly positioned in the vertical plane of the slots 6 of the grippers 4 and 5 irrespective of the size or style of last upon which the upper is positioned. To position singly a plurality of different sizes or styles with the tip-seam line thereon in an invariable position relative to the lasting devices the guide 40 carries a horizontal shaft 48 which is provided at one end with coarse threads 49 and at the other end with fine threads 50. The coarse and fine threads engage respectively with similar threads in the slides 39 and 44. The shaft 48 carries a gear 51 which is driven from a horizontal shaft 52 (Fig. 4) through a gear 53 carried by the shaft 52. The shaft 52 is connected by a universal joint 54 to a shaft 55 which is journaled in a bearing 56 carried by a universal joint 57 (Fig. 4) supported by a bracket 58 on the machine frame. The shaft 55 carries a hand wheel 59 by means of which the operative may slide the heel and forepart rests toward or from each other to properly position the last in the machine. When the last is properly positioned in the machine the face of the heel of the last engages the heel rest 34, the tip-end of the insole on the last is flush with the tip-end of the rest 36, the mark on the rest 36 registers with the lead line of the last, and the tip-seam line on the last lies in the vertical plane of the slots 6.

In order to clamp the positioned last to prevent its displacement during the lasting operation the usual spindle socket 60 is engaged by a bent rod 61 (Figs. 1 and 2) which binds the last upon its supporting rests. To this end the free end of the rod 61 is engaged by the sloping faces of a block 63 which is secured to a yoke 64 pivoted on a pin 65 (Fig. 1) carried by the slide 39. The block 63 is actuated to press the rod 61 into binding engagement with the last 2 by a three-armed lever 66 which is mounted in a slot 67 (Fig. 1) formed in the slide 39 and pivoted to a pin 68 carried by the slide. The lever 66 is provided with a handle 69 for engagement by the operative. In order that the clamp may adapt itself to the varying heights of lasts the lever 66 is yieldingly connected to the yoke 64. To this end a rod 70, pivoted at 71 to the yoke 64, is loosely embraced by a block 72 (Fig. 2) pivoted to the lever 66. Interposed between the block 72 and a shoulder 73 on the rod is a spring 74 coiled around the rod. With this construction manipulation of the handle 69 in one direction tensions the spring 74 which yieldingly presses the rod 61 into binding engagement with the last. It will be noticed

from an inspection of Fig. 2 that the pivots 65 68, 71 and 72 constitute the three pivots of a toggle which when made locks the clamp in its clamping position. It will also be noticed that the spring 74 interposed between the pivots 71 and 72 provides a yielding arm 70 for the toggle.

After the last with the upper thereon has been properly positioned and clamped in the machine the grippers are engaged with the upper around the forepart and then the last 75 and grippers are relatively actuated to stretch the upper on the last. To relatively actuate the last and grippers the carrier 42 is connected to a vertical rod 75 (Fig. 2) which is provided at its lower end with a 80 rack 76 engaged by a pinion 77 which is driven from a suitable source of power to elevate the last.

It is desirable to automatically unclamp the last during the elevation thereof in order 85 to prepare for the ready removal of the lasted shoe from the machine. To this end the lever 66 (Figs. 1 and 2) is pivoted at 102 to an arm 103 which in turn is pivoted to a block 104 mounted to slide in ways 105 90 carried by the bracket 79. Interposed in the path of movement of the block 104 is a slide 106 which interrupts the movement of the block 104 responsive to the elevating movement of the last thus causing the lever 95 66 to turn about its pivot 102 and thereby break the toggle to free the rod 61. The return of the toggle to its broken position is retarded by friction blocks 107 (Fig. 1) arranged on opposite sides of the guide 39 in 100 position to engage friction surfaces 108 (Fig. 2) on the lever 66. The slide 106 is adjustably mounted to move into and out of the path of the block 104 so that the automatic unclamping of the last may or may 105 not take place at the will of the operative.

It will be apparent to those skilled in the art that changes may be made in the details of structure, the described and illustrated embodiment thereof being intended as an 110 exploitation of its underlying essentials, the features whereof will be definitely stated in their true scope in the claims hereto appended.

What is claimed as new, is:—

1. In a lasting machine the combination of 115 means for supporting a shoe with the tip-seam of the upper in full view of the operative comprising a pair of bottom rests, and means for differentially adjusting the bottom rests to position singly lasts of different sizes with the tip lines thereon in the same invariable position, substantially as described.

2. In a lasting machine the combination of 125 a support for an assembled shoe comprising a back rest for engaging the face of the heel end of the shoe, a heel seat rest arranged to

engage the heel seat of the insole, and a forepart rest arranged to engage the tip end of the insole, and means for centering the shoe in the machine comprising a pair of 5 arms arranged to embrace the counter of the shoe and an indicating mark on the forepart rest arranged in the center line of the machine which registers with the lead line on the last, substantially as described.

10 3. A lasting machine, having, in combination, means for supporting a shoe with the tip-seam of the upper in full view of the operative and adjusting means for said support enabling it to support any one of a 15 plurality of lasts of different sizes with the tip lines thereon in invariable position, substantially as described.

4. A lasting machine, having, in combination, a support for an assembled shoe 20 comprising a pair of bottom rests arranged to engage respectively the heel seat and tip-end of the insole, and means for differentially adjusting the rests comprising a rod provided with fine and coarse threads which 25 engage similar threads on the tip-end and heel seat rests respectively, substantially as described.

5. A shoe machine, having, in combination, a shoe support comprising a pair of 30 bottom rests arranged to engage respectively the heel seat and tip-end of the insole, means for differentially adjusting the rests comprising a rod provided with fine and coarse threads which engage similar threads on the 35 tip-end and heel seat rests respectively, means for rotating the rod comprising a shaft geared to the rod, and a hand wheel for rotating the shaft, substantially as described.

40 6. A shoe machine, having, in combination, a work support, and a clamp for binding the work on the support including a toggle having a yielding arm, substantially as described.

45 7. A shoe machine, having, in combination, a work support, a clamp for binding the work including a toggle, a manually operated device for making the toggle, and means for automatically breaking the toggle, substantially as described.

50 8. A shoe machine, having, in combination, a work support, a clamp for binding the work, including a toggle, a manually operated device for making the toggle, means for automatically breaking the toggle, and a friction device for retarding the return of the toggle to broken position, substantially as described.

60 9. A shoe machine, having, in combination, a shoe support, and a clamp for binding the shoe on the support comprising a rod arranged to engage the spindle hole in the last, a block arranged to engage the rod, and a toggle for locking the block in its

rod-engaging position, substantially as described.

10. A shoe machine, having, in combination, a shoe support, a clamp for binding the shoe on the support comprising a rod arranged to engage the spindle hole in the 70 last, a block arranged to engage the rod, a pivoted yoke for the block, and a toggle for locking the block in its rod-engaging position, the central pivot of which is carried by the yoke and the other pivots of which 75 are carried by a pivoted lever provided with an actuating handle, substantially as described.

11. A shoe machine, having, in combination, a shoe support, a clamp for binding the 80 shoe on the support comprising a rod arranged to engage the spindle hole in the last, a block arranged to engage the rod, a toggle for locking the block in its rod-engaging position, and automatic means for 85 breaking the toggle to release the rod during the elevation of the support, substantially as described.

12. A shoe machine, having, in combination, a shoe support, a clamp for binding 90 the shoe on the support comprising a rod arranged to engage the spindle hole in the last, a block arranged to engage the rod, a toggle for locking the block in its rod-engaging position, and a lever provided with 95 an operating handle for manually making and breaking the toggle, substantially as described.

13. A shoe machine, having, in combination, a vertically movable shoe support, a 100 clamp for binding the shoe on the support comprising a rod arranged to engage the spindle hole on the last, a block arranged to engage the rod, a toggle for locking the block in its rod-engaging position, a lever provided with an operating handle for manually making and breaking the toggle, and 105 means for automatically breaking the toggle to release the rod during the elevation of the support, substantially as described. 110

14. A shoe machine, having, in combination, a vertically movable shoe support, a clamp for binding the shoe on the support comprising a rod arranged to engage the spindle hole in the last, a block arranged to engage the rod, a toggle for locking the block in its rod-engaging position, a lever provided with an operating handle for manually making and breaking the toggle, and means for automatically breaking the toggle 115 to release the rod during the elevation of the support comprising a slide, mounted to move with the support, connected to the operating lever and a device for interrupting the movement of the slide, substantially 120 as described.

15. A shoe machine, having, in combination, a shoe support and a clamp for bind-

ing the shoe on the support comprising a rod arranged to engage the spindle hole in the last, and a block having sloping faces arranged to engage the rod, substantially as described.

16. A shoe machine, having, in combination, a shoe support and a clamp for binding the shoe on the support comprising a rod

arranged to engage the spindle hole in the last and a block having sloping faces of greater length than the diameter of the rod arranged to engage the rod, substantially as described.
